UNITED STATES PATENT OFFICE.

DON D. BRANT, OF LONG BEACH, CALIFORNIA.

SUCKER-ROD ELEVATOR.

Application filed December 13, 1926. Serial No. 154,501.

My invention is a sucker rod elevator for use in deep wells, such as oil wells, for raising and lowering the sucker rod, the pump and polish rods, and the like.

5 In the use of elevators for raising sucker rods and the like, in the type having latches to hold the rod in place, it has been found that the rods frequently become bent due to the body of the elevator becoming tilted so 10 that the rods bears against either the latches or the back of the body portion, thus creating a leverage on the rod which bends same.

An object of my invention is to overcome this and other defects by constructing the 15 body of the elevator structure and its support from a bale so that the rod is suspended slightly off center and the body of the elevator has a tendency, when weight is brought on it, to tilt backwardly thereby 20 displacing the rod to a greater extent away from the latches than with the ordinary type of elevator.

A further object of my invention is forming the body of the elevator with a cut out 25 portion at the rear of the slot or opening for the rod so that when the device is tilted the rod will not come into contact with the back portion of the body of the elevator, the rod being suspended by opposite conical bearing 30 surfaces which engage a shoulder on the rod.

My invention in its various aspects is illustrated in the accompanying drawings, in which:

Figure 1 is a horizontal section on the line 35 1—1 of Fig. 3 in the direction of the arrows, and may be considered as a plan of the body structure of the elevator, such body structure being partly cut away on the line of the latches to show the clearance of the rod in 40 reference to the center part of the body and latches.

Figure 2 is a vertical section on the line 2—2 of Fig. 1 in the direction of the arrows.

Figure 3 is a front elevation on a reduced 45 scale, as if taken in the direction of the arrow 3 of Fig. 1, showing the bale attached to the elevator.

Figure 4 is a sketch similar to Fig. 2 illustrating the position of the rod when the 50 elevator is tilted down at the back.

Figure 5 is a view similar to Fig. 4 showing the position of the rod relative to the elevator when the latter is tilted down at the front.

55 The elevator is constructed with a U-shaped body 1 having a central opening 2

extending vertically therethrough, and with the open mouth passage 3 for insertion of the rods. The body has a pair of opposite recesses 4 on the front portion and a pair of latches 5 are pivotally mounted on vertical 60 pivot pins 6, secured in the upper and lower part of the body across the recesses. A spring 7 operates between the gripping end 8 of the latch and an abutment 9 of the body 65 of the elevator. The latches may be operated by a hand grip end 10.

The central opening has a pair of partly conical bearing surfaces 11 positioned 70 directly opposite and the inner side walls 12 are partly curved to accommodate the rods to be fitted therein. The back portion 13 is cut back beyond the bearing surfaces 11 so that a rod is supported on opposite sides. It will be noted that the center portion 14 of 75 this back wall of the opening is substantially vertical and that the upper and lower parts 15 and 16 have an inclination backwardly for a purpose hereunder set forth.

Gudgeons 17 are constructed on the opposite sides of the body, being preferably an 80 integral casting therewith, and the bale 18 having eyes 19 is swivelly mounted thereon, there being preferably washers 20 and cotter pins 21 holding the bale in position. On 85 the bale I prefer to have a bulge 22 to allow the men working with the elevator to be able to grip the bale, even when it is coated with oil and therefore slippery.

Referring to Fig. 1, the axial line of the 90 gudgeons and hence the support from the bale is designated by the numeral 23 and the center line of the support for the rod is indicated by the line 24, the rod being designated by the numeral 25 and having a 95 shoulder 26 with a tapered part 27 between the main body of the rod and the collar or shoulder. The rod also preferably has a squared section 28 with a shoulder on the upper part which may be fitted in the opening if desired. Therefore the axial center of the gudgeons in relation to the rod may be designated by the numeral 29, and the vertical axial line of the rod may be designated by the numeral 30.

100 The manner of using and functioning of my elevator is substantially as follows:

It will be understood that the rods may be inserted in the ordinary manner by forcing the elevator against the rod or vice versa 110 so that the latches are pressed back, allowing the insertion of the rod in the opening

2. The elevator is then raised until the rod is seated on the conical bearing surfaces 11, being supported on its opposite sides by the curved portion 27 or the shoulder 26, in accordance with the size and the curvature of the rod. When the elevator device is horizontal, as shown in Fig. 2, the center line 30 of the rod is positioned rearwardly of the center of rotation 29 of the elevator 10 on account of the axial line 23 of the gudgeons being set forwardly of the supporting center line 24. Therefore when weight is brought on the elevator, due to lifting or supporting rods, the elevator body 15 tilts backwardly and downwardly, as illustrated in Fig. 4. This causes the portion of the rod below the shoulders 26 to swing rearwardly towards the rear wall 14, 15 and 16 of the opening 2 and it will be seen, 20 on account of the inclination of the ends 15 and 16, that the rod does not touch this back wall and hence there is no leverage against the rod to bend same. Therefore, should by chance the rod engage the back 25 wall, on account of the long leverage between the shoulder and the engaging point, the rod would not be apt to bend.

In Fig. 5 the body of the elevator is tilted forward indicating a position in which the 30 center line 29 of the gudgeons is in alignment with the vertical center line 30 of the rod. When the device is tilted in this direction, such tilt is against the natural pull of the rod and in approximately such position the ends 8 of the latches 5 would engage the rod or possibly the rod might swing slightly forward of the center. In prior 35 constructions the rods have been bent usually by tilting of the elevator relative to the rod so that the rod engages the latches, there then being a short leverage between the shoulders and the engaging latches and giving the rod a bend. It will thus be seen that my construction of an elevator having 40 two opposite surfaces of somewhat conical shape to engage the rod with a large space behind the rod and between the rod and the latches, together with the offset centers of gudgeons and the rods, prevents to a great 45 extent their bending of the rods. It is to be understood that in Figs. 4 and 5 the offset of such centers has been exaggerated for the sake of illustration. It will be apparent that my elevator may be used in the 50 ordinary manner of those now on the market and covered by patents.

A characteristic feature of my invention is that the partial curve 12 in the side walls

between which the sucker rod depends, being supported on the conical bearing surfaces 11, 60 extends from top to bottom of the U-shaped elevator body. Moreover, the center line of the curved inner walls 12 and the curved seats 11 is set inwardly to one side from the axial line of the gudgeons. That is, 65 these are in two parallel planes, when the upper and lower surface of the supporting body is horizontal.

Various changes may be made in the principles of my invention without departing 70 from the spirit thereof, as set forth in the description, drawings and claims.

I claim:

1. A sucker rod elevator comprising in combination a body structure having a central opening with an entrance at the front and having a back wall, side walls leading from the front opening to the back wall, said side walls having opposite vertical curved sections parallel to each other and 75 extending from top to bottom of the body structure, means to suspend the body structure and means to form a closure for the said central opening.

2. A sucker rod elevator comprising in 80 combination a body structure having a central opening with an entrance at the front and having back and side walls having opposite curved sections parallel to each other, gudgeons forming a pivotal support for the 85 body structure, the axis of said gudgeons being in a plane forward of the vertical plane of the axis of the curved sections of the side walls, and means forming a closure for the entrance of the opening. 95

3. A sucker rod elevator comprising in combination a body structure having a central opening with an entrance at the front and having back and side walls, the side walls having curved sections parallel to 100 each other and extending from top to bottom of the body structure, there being conical seats at the termination of each curved section at the top and bottom of the body structure, gudgeons forming a pivotal support for the body structure, the axial line of the gudgeons being forward of the vertical plane of the curved portions of the side walls, the back wall being beveled at the 105 top and bottom rearwardly of the body structure, and latches forming a closure for the entrance of the central opening. 110

In testimony whereof I have signed my name to this specification.

DON D. BRANT.
